(57) **CLAIM**

The ornamental design for an operator device with display, as shown and described.

DESCRIPTION

FIG. 1 is a top left side perspective view of the operator device with display, showing my new design;

FIG. 2 is front view thereof;

FIG. 3 is a left side elevational view thereof;

FIG. 4 is a right side elevational view thereof;

FIG. 5 is a top view thereof; and,

FIG. 6 is a bottom view thereof.

The broken lines form no part of the design to be patented. The broken lines in FIGS. 3, 4, 5 and 6 show environment related to the claimed design and are for illustrative purposes only.
